(57) **CLAIM**

The ornamental design for a mobile phone, as shown and described.

DESCRIPTION

1.1 is a front view of a mobile phone showing the new design;

1.2 is a back view thereof;

1.3 is a left view thereof;

1.4 is a right view thereof;

1.5 is a top view thereof;

1.6 is a bottom view thereof;

1.7 is a perspective view thereof;

1.8 is a front view of the mobile phone of reproduction 1.1 showing in a closed state;

1.9 is a left view thereof;

1.10 is a top view thereof; and

1.11 is a perspective view thereof.

The broken lines shown in the drawings illustrate portions of the mobile phone that form no part of the claimed design; The dot-dash broken lines in the drawings define the boundaries of the claimed design and form no part thereof.

1 Claim, 11 Drawing Sheets
